UNITED STATES PATENT OFFICE.

ROBERT F. EICHNER, OF ROCHESTER, NEW YORK, ASSIGNOR TO HICKOK MANUFACTURING COMPANY, OF ROCHESTER, NEW YORK, A CORPORATION OF NEW YORK.

DESIGN FOR A BELT BUCKLE.

Application filed July 11, 1928. Serial No. 27,454. Term of patent 3½ years.

To all whom it may concern:

Be it known that I, ROBERT F. EICHNER, a citizen of the United States, residing at Rochester, in the county of Monroe and State of New York, have invented a new, original, and ornamental Design for a Belt Buckle, of which the following is a specification, reference being had to the accompanying drawing, forming part thereof.

In the drawing:

Fig. 1 is a front view of a belt buckle, showing my new design; and
Fig. 2 is an end view thereof.

I claim:

The ornamental design for a belt buckle, as shown.

ROBERT F. EICHNER.
